UNITED STATES PATENT OFFICE.

KATHERYNE P. MALON, OF CHICAGO, ILLINOIS

PRESS.

Application filed January 23, 1922. Serial No. 531,280.

To all whom it may concern:

Be it known that I, KATHERYNE P. MALON, a citizen of the United States, and a resident of the city of Chicago, county of Cook, and

5 State of Illinois, have invented certain new and useful Improvements in Presses, of which the following is a specification.

My invention relates to improvements in presses, and more especially to filtering 10 means for filtering liquids expressed by said presses, the object of the invention being to provide a simple and effective arrangement of this character which is of simple construction and efficient in operation.

15 Other objects will appear hereinafter.

The invention consists in the combinations and arrangements of parts hereinafter described and claimed.

The invention will be best understood by 20 reference to the accompanying drawings forming a part of this specification, and in which,

Fig. 1 is a partial side view of a portion 25 of the hydraulic press embodying the invention;

Fig. 2 is a transverse section of the same taken substantially on line 2—2 of Fig. 1;

Fig. 3 is an enlarged side view of a filter 30 bag employed in the construction;

Fig. 4 is a section taken on line 4—4 of Fig. 3;

Fig. 5 is a bottom plan view corresponding 35 with Fig. 3; and

Fig. 6 is a section taken on line 6—6 of Fig. 3.

The preferred form of construction as 40 illustrated in the drawings comprises the usual horizontal hydraulic press having the usual side bars 7 and abutment 8 with the usual pressure frames 9 arranged as indicated, each frame 9 being formed of vertical and horizontal slats as shown, one horizontal slat 10 being extended laterally to rest upon the side bars 7 as best indicated in Fig. 2.

45 So much of the construction is an old and well known form of construction employed in such presses for expressing liquid matter from meal, ground meat, or the like and forms no part of my present invention except in so far as the same cooperates with other features to be presently described.

Each of the pressure frames 9 is provided 50 at the bottom on opposite sides with hooks 11 adapted to detachably engage pins 12 on the adjacent frame and whereby said frames may be readily positioned in the press in

spaced relation with each other. Each of the pressure frames 9 is also provided at its bottom with a horizontal cross slat 13 forming a supporting ledge as indicated and a 60 cloth filter bag 14 is arranged between each pair of the pressure members 9. Each filter bag is made tubular in form and open at both top and bottom, being provided at the top with side flaps 15 by means of which 65 the bag may be secured in place between two of the pressure frames 9 by tacks or otherwise as indicated. At the bottom each bag is provided with upwardly turned flaps 16 forming loops as shown for the reception of 70 stiffening plates 17 arranged in said loops across opposite sides of the lower end of the bag as shown.

In use each bag is folded or wrapped around the stiffening plates 17 and positioned between the pressure members 9 as indicated with the plates 17 supported on corresponding strip 13 in an inclined position as shown, the hooks 11 being utilized to hold the pressure members 9 in proper spaced 75 relation to support the plates 17 in such inclined position. The bag 14 is then filled with the material, such as cotton seed meal or the like from which it is desired to express the liquid and the press operated to 80 force the frames 9 toward each other thus compressing the matter in the bags 14 and forcing the liquid through the walls of the bag. When the liquid has thus been completely expressed and it is desired to discharge the matter from the bags 14 the press 85 is operated to relieve the pressure and the pressure frames 9 separated sufficiently to permit the plates 17 to fall or tumble from the supporting strips 13 thus automatically 90 opening the bags and permitting of discharge of the exhausting material. I have 95 illustrated but one bag and one pair of the pressure members 9 but it is to be understood that usually a plurality of said frames and bags will be employed. In this manner a 100 simple and effective arrangement is provided for sealing the bottoms of the bags permitting of ready discharge of the contents thereof.

105 While I have illustrated and described the preferred form of construction for carrying my invention into effect, this is capable of variation and modification without departing from the spirit of the invention. I, 110 therefore, do not wish to be limited to the precise details of the construction set forth,

but desire to avail myself of such variations and modifications as come within the scope of the appended claims.

Having described my invention, what I claim as new and desire to secure by Letters Patent is:

1. A press comprising adjoining pressure members; and a filter bag of flexible material inserted between said members, said bag being open at one end and a complete portion of the open end of said bag being folded upon itself and arranged between said pressure members so as to cause said complete folded end to press against the side of said bag upon the approach of said pressure members, substantially as described.

2. A press comprising adjoining pressure members; a filter bag inserted between said members, said bag being open at one end; a stiffening plate arranged at the open end of said bag, said bag being folded against one side of said plate; and means for supporting said plate between said pressure members in an inclined position, substantially as described.

3. A press comprising adjoining pressure members; a filter bag inserted between said members, said bag being open at one end; a stiffening plate arranged at the open end of said bag, said bag being folded around and against one side of said plate; and means for supporting said plate between said pressure members in an inclined position, substantially as described.

4. A hydraulic press comprising adjoining pressure members; a filter bag inserted between said members, said bag being open at its lower end; stiffening plates secured to opposite sides of said bag adjacent the open end thereof, said bag being folded against one side of one of said plates; and means for supporting said plates between said pressure members in an inclined position, substantially as described.

5. A press comprising adjoining pressure members; a filter bag inserted between said members, said bag being open at its lower end; stiffening plates secured to the opposite sides of said bag adjacent the lower end thereof, said bag being folded around said plates; means for supporting said plates between the lower portions of said pressure members in an inclined position; and de-

tachable means for securing said pressure members in spaced relation to each other, substantially as described.

6. A press comprising adjoining pressure members; a cloth filter bag arranged between said members, said bag being open at the bottom; stiffening plates secured to opposite sides of said bag at the lower end thereof, said bag being folded around said plates; a supporting ledge on one of said pressure members adjacent the bottom thereof adapted and arranged to support said plates in an inclined position between said pressure members; and detachable hooks securing said pressure members in spaced relation to each other, substantially as described.

7. A filter bag for presses made with a normally open end and a stiffening plate arranged across one side of said bag adjacent the open end thereof, said bag being adapted and arranged to be folded against one side of said plate for sealing purposes, substantially as described.

8. A filter bag for presses open at the bottom; and stiffening plates arranged across opposite sides of said bag adjacent the bottom thereof, said plates being arranged to be folded against the side of said bag for sealing purposes, substantially as described.

9. A filter bag for presses comprising a tubular cloth body open at both top and bottom; and a stiffening plate secured across one side of the bottom of said bag, substantially as described.

10. A filter bag for presses comprising a tubular cloth body open at both top and bottom; and stiffening plates secured across opposite sides of the bottom of said bag, substantially as described.

11. A filter bag for presses made of flexible material and normally open at one end, a complete portion of the open end of said bag being folded upon itself and arranged to press against the side of said bag, substantially as described.

In testimony whereof I have signed my name to this specification in the presence of two subscribing witnesses.

KATHERYNE P. MALON.
